Primary Examiner — Susan Bennett Hattan*Assistant Examiner* — Marie Fast Horse(74) *Attorney, Agent, or Firm* — Schwegman Lundberg & Woessner, P.A.(57) **CLAIM**

The ornamental design for eyeglasses, as shown and described.

DESCRIPTION

FIG. 1 is a top-left-front perspective view of eyeglasses, showing our new design.

FIG. 2 is a top-right-front perspective view thereof.

FIG. 3 is a bottom-left-rear perspective view thereof.

FIG. 4 is a front elevation view thereof.

FIG. 5 is a left elevation view thereof.

FIG. 6 is a right elevation view thereof.

FIG. 7 is a rear elevation view thereof.

FIG. 8 is a top plan view thereof; and,

FIG. 9 is a bottom plan view thereof.

The shade lines show surface contour and not surface ornamentation.

1 Claim, 9 Drawing Sheets(56)
